(57) **CLAIM**

The ornamental design for a waterproof case for electronic device, substantially as shown and described.

DESCRIPTION

FIG. 1 is a perspective view of the design, principally showing the front, right side and top,

FIG. 2 is an elevational view of the front,

FIG. 3 is a top plan view,

FIG. 4 is a right side elevational view,

FIG. 5 is a left side elevational view,

FIG. 6 is a rear elevational view,

FIG. 7 is a bottom view; and,

FIG. 8 is a rear perspective view.

The broken line showing of environment in the drawings is included for the purpose of illustrating only and forms no part of the claimed design.
